(57) **CLAIM**

I claim the ornamental design for mosquito exterminator, as shown and described.

DESCRIPTION

FIG. 1 is a front view of a mosquito exterminator.

FIG. 2 is a rear view of a mosquito exterminator.

FIG. 3 is a left view of a mosquito exterminator.

FIG. 4 is a right view of a mosquito exterminator.

FIG. 5 is a top view of a mosquito exterminator.

FIG. 6 is a bottom view of a mosquito exterminator; and,

FIG. 7 is a perspective view of a mosquito exterminator. The broken lines depict environmental structure and are included for the purpose of illustration only and form no part of the claimed design.
